UNITED STATES PATENT OFFICE.

DANIEL D. SCHRAGER AND RUDY N. SCHRAGER, OF CHICAGO, ILLINOIS.

DESIGN FOR A WEDDING RING (MASONIC).

Application filed January 30, 1926. Serial No. 16,351. Term of patent $3\frac{1}{2}$ years.

To all whom it may concern:

Be it known that we, DANIEL D. SCHRAGER and RUDY N. SCHRAGER, citizens of the United States, residing at Chicago, in the county of Cook and State of Illinois, have invented a new, original, and ornamental Design for Wedding Rings (Masonic), of which the following is a specification, reference being had to the accompanying drawing, forming part thereof.

The decoration appearing on the edge view of the ring illustrated in Figure 2 extends entirely around the surface thereof.

We claim:

The ornamental design for a wedding ring (Masonic), as shown.

In testimony whereof we affix our signatures.

DANIEL D. SCHRAGER.
RUDY N. SCHRAGER.
